[57] **CLAIM**

The ornamental design for a cassette tape, substantially as shown.

DESCRIPTION

FIG. 1 is a perspective view of a cassette tape showing my design as seen from the top, showing my new design;

FIG. 2 is a perspective view thereof as seen from the bottom;

FIG. 3 is a front elevational view thereof;

FIG. 4 is a rear elevational view thereof;

FIG. 5 is a top plan view thereof;

FIG. 6 is a bottom plan view thereof; and

FIG. 7 is a left end elevational view, which view is symmetrical to a right end elevational view thereof.
